UNITED STATES PATENT OFFICE.

PHILLIP D. DOYLE, OF SOMERVILLE, MASSACHUSETTS.

DRAW-HOOK AND DRAW-BAR FOR WAGONS.

SPECIFICATION forming part of Letters Patent No. 769,793, dated September 13, 1904.

Application filed May 5, 1904. Serial No. 206,521. (No model.)

To all whom it may concern:

Be it known that I, PHILLIP D. DOYLE, a citizen of the United States, residing in Somerville, in the county of Middlesex and State of Massachusetts, have invented a new and Improved Draw-Hook and Draw-Bar for Wagons, of which the following is a specification.

This invention relates to draw-hooks and draw-bars for double wagons, mostly wagons used for teaming purposes.

As heretofore constructed, as far as I am aware, the draw-hooks and draw-bars are made in a single integral piece or from two pieces, which are afterward welded together, so that the hook and bar are, when ready for use, practically a single integral piece. The wear produced by the whiffletree is of course on the hook and in practice on a particular portion of the hook. When this portion of the hook is worn nearly through, the entire draw-hook and draw-bar are useless, and a new hook must be substituted for the old one.

It is the particular object of this invention to produce a draw-hook and draw-bar which is separable, whereby when the hook becomes worn it can be removed from the draw-bar without disturbing the latter or its position on the wagon-gear and a new hook substituted.

The nature of the invention is fully described below, and illustrated in the accompanying drawings, in which—

Figure 1 is a side elevation of a portion of a gear of a wagon and a cross vertical section of the forward axle with my improved draw-hook and draw-bar shown in position in elevation. A portion of the pole is also illustrated. Fig. 2 is a plan view of the same, taken on line 2 2, Fig. 1. Fig. 3 is an enlarged plan view of the invention, a portion of the bar being broken off. Fig. 4 is a cross-section taken through the cross-bar and a longitudinal section taken on line 4 4, Fig. 3.

Similar letters of reference indicate corresponding parts.

45 *a* represents an ordinary frame of the gear of a wagon, *b* being the fifth-wheel. *c* is the pole, *d* the front axle, and *e* the cross-bar, all constructed as usual.

Secured to the front axle *d* by means of a

clip *f* and suitable nuts *g*, near each end of the axle *d*, is a draw-bar *h*, the front end *h'* of which is thickened downwardly and is integral with the main portion *h*. This main portion extends upward at an angle, as shown in Fig. 1, from the under side of the axle, and the front end or head *h'* is provided next its upper surface with oppositely-extending wings *h''*, Fig. 3, by means of which the draw-bar is secured to the cross-bar *e* by suitable bolts. The downwardly-extending portion *h'* of the draw-bar is provided with a horizontal hole, through which the squared shank *l* of the hook *k* extends, the shank fitting in the said hole, and thereby preventing rotation.

The rear end of the shank is screw-threaded to receive a nut *n*, which may be locked in place, if desired, as shown in Fig. 4. The draw-hooks, draw-bars, and their connecting means are exactly alike and are applied to the cross-bar in the usual locations.

It will readily be seen that when a hook *k* has become so much worn that it is no longer safe or strong the nut *n* can be removed and the shank *l* withdrawn from the portion *h'* and the shank of a new hook inserted. Thus it is not necessary to remove and lose the draw-bar, as is the case when the draw-bar and hook are in a single piece.

The advantage of this construction is evident when it is considered that practically all the wear is on the hook and that a single draw-bar will outwear many draw-hooks.

Having thus fully described my invention, what I claim, and desire to secure by Letters Patent, is—

1. In a draw-hook and draw-bar for wagons, the draw-bar *h* formed at its forward end with the thickened head *h'*; and the draw-hook *k* removably secured in and extending forward from said head, for the purpose set forth.

2. In a draw-hook and draw-bar for wagons, the draw-bar *h* formed at its forward end with the thickened head *h'*, and provided at said end with the oppositely-extending wings *h''*, whereby the draw-bar may be secured to the under side of the cross-bar making a portion of the wagon-gear; and the draw-hook *k* provided with the shank *l* removably secured in

and extending forward from said head, for the purpose set forth.

3. A separable draw-hook and draw-bar for wagons, the shank of said draw-hook being 5 removably secured to the forward end of the draw-bar, for the purpose set forth.

In testimony whereof I have signed my name

to this specification in the presence of two subscribing witnesses.

PHILLIP D. DOYLE.
